FULL-FASHIONED HOSIERY

Abrasha Wilcher, Manchester, N. H., and Melvin J. Gordon, Brookline, Mass., assignors to Melvin J. Gordon, Sadye Z. Gordon, and Natalie G. Stone, doing business as Manchester Hosiery Mills, Manchester, N. H.

Application January 13, 1949, Serial No. 70,754

1 Claim. (Cl. 66—173)

1 The present invention relates to women's full fashioned hosiery which is knit on a flat knitting machine in the form desired and then seamed together by joining with a longitudinal seam which extends the entire length of the hose in a position corresponding to the back center line of the leg.

In the manufacture of such hosiery, a welt is usually formed at the top of the hose which ordinarily is of the order of 3½" or 4" wide. This welt is knit flat upon the knitting machine. The flat fabric is knit 7 to 8 inches and then doubled by transferring the first stitches off the welt bar onto the needle bar thus forming a double fabric which is commonly known as the welt or double welt and the end of the welt is joined with the body of the hose. In fact the stocking is usually knitted commencing at the end of the welt and continuing down to the foot section while the longitudinal seam is formed commencing at the foot end and ending on the inside of the welt. In order to be able to remove the seaming guides and cup of the seaming machine after forming this joining seam, it is necessary to leave a space at the end of the welt so that the stocking may be withdrawn from the seaming guides. This opening in the welt at this point is a weakness in the hosiery, and this weakness is particularly emphasized when the hosiery is supported at this point by the garter, since very frequently the garter is clamped to the hosiery at the point where the seam is left open, with the result that only one thickness of the stocking is held by the garter rather than both thicknesses of the welt.

The present invention overcomes this difficulty by the formation of a garter block or section on the external face or side of the welt which garter block section is of the same or greater strength as the doubled formed welt extending around the top of the hose where no opening exists. The garter block of the present invention may extend for a narrower or wider distance on either side of the joining seam at the back of the garter. For best purposes it should be somewhat wider than the welt opening on the inner side so that if the top of the welt is distorted by stretching transversely, the block on the side of the welt will still cover the opening on the inner side.

The invention will be more fully described in the specification below when taken in connection with the drawings illustrating an embodiment of the same, in which:

Figure 1 shows the top full fashioned hose as viewed from the outside of the stocking looking at the longitudinal seam at the center.

2 Figure 2 shows a fragmentary view looking at the stocking against the inner side of the welt at the top of the hose in substantially the same position as shown in Figure 1, and,

5 Figure 3 shows a sectional view taken on the line 3—3 of Figure 1.

In the drawings, the section 1 of the hose up to the light demarcation line 2 comprises a knitted fabric of the thinnest denier or lightest weight thread in the hose. In a well made hose this thread may be of the order of 30 denier. Above this section of the hose is knitted an after welt, knit with a heavier thread, perhaps 50 denier, as illustrated in the section 3 between the demarcation lines 2 and 4. The top welt part of the hose may be knitted with the same heavier thread as for instance of a 50 denier. This may be the thickness of the thread or of the total carrier strands employed in the section 5.

20 As shown more clearly in Figure 3, the welt begins on the inside at the line 4 marking the beginning of a heavier thread than the section in the lower leg section of the hose. This welt extends on the inside to the top of the hose where a finishing top stitch 7 may be applied and then down on the outer side at 8 to the line 4 where lighter courses are formed in the knitting.

25 In the initial flat knitting of the hose, the welt side edge is substantially a straight line and continues as such down the side along the top part of the flat knitted hose. When however these edges are stitched together to form the back seam of the hose, the fact that the seam is stopped before the inner end of the welt provides an oval shaped opening 9 due to the naturally transverse stretch of the knitted fabric.

30 In this section where the opening 9 is so formed, a block 10 is made on the outside section of the welt on either side of the longitudinal joining seam 11. This block may be formed by adding extra thread for each course commencing at the top finishing edge 7 down to the end of the welt on the outer side as defined by the line 4. The extra thread is preferably carried only part way along the welt, preferably an equal distance on both sides as defined by the lines 12 and 13. (See Fig. 1.) If the welt thread used is 50 denier, the added thread may be of equal or less thickness, thus making the section 10 substantially as strong as the double thickness of the rest of the welt band itself.

35 The formation of the block in the welt on the outside makes it unnecessary for the wearer of the hose to avoid putting the garter over the seam within the area 9, but in addition to this,

provides a reinforced region at both sides of the seam at the top of the hosiery which is the logical place where the garter is to be applied. In fact the garter should be applied to this block section if the individual wishes to have the seam extend in a straight line with reference to the symmetry of the leg. If the garter is placed to one side avoiding opening 9 then the hose will not be held straight on the leg and there will be a tendency for it to twist to the side making an unsightly 10 appearance of the seam.

In addition to this it will of course be noted that by applying the block on the outside of the welt in the section on either side of the seam, the holding region for the garter will be materially strengthened without in any way destroying the balance of the stocking, that is, making it top heavy and without interfering also with the symmetry of the stocking since the garter block extends on either side of the central longitudinal 15 seam of the stocking.

The invention may be applied to any type of knitted full fashioned hosiery of silk, nylon, rayon, or other materials.

Having now described our invention, we claim: 21

In a full-fashioned flat knit seamed hose having a top double welt with an opening along the seam at the inside of the welt, a section in the outer side of the welt on each side of the seam 5 knit of heavier thread than the remainder of the welt, said section being substantially less in extent than half the circumference of the hose at the top and greater than the width of the opening and extending throughout the vertical extent of the welt.

ABRASHA WILCHER.
